J. F. Reigart.

United States Patent Office.

WILLIAM E. WILCOX, OF PEORIA, ILLINOIS, ASSIGNOR TO HIMSELF AND THOMAS H. WILLS, OF SAME PLACE.

Letters Patent No. 93,150, dated July 27, 1869.

IMPROVED RAILWAY-CAR-AXLE BOX

The Schedule referred to in these Letters Patent and making part of the same.

To all whom it may concern:

Be it known that I, WILLIAM E. WILCOX, of Peoria, Peoria county, State of Illinois, have invented new and useful Anti-Friction Revolving Cylinders and Sectional Rollers Combined for Car-Axle Boxes and Shafting; and I do hereby declare the following to be an exact description of the same, reference being had to the accompanying drawings, and to the letters of reference marked thereon, making a part of this specification.

Figure 1 represents the end view of the box, axle, rollers, and cylinders on the inside.

Figure 2 represents a top sectional and longitudinal view of the same.

The nature of my invention consists in the combination and arrangement of two cylinders, operating on the upper side of the axle, with a flange on the outer end of the axle, and anti-friction sectional rollers on journals of the cylinders, and the object is to lessen the friction of the axle, and prevent the axle from wobbling.

A represents the end and top of the cast-iron box, in which the axle B revolves, the journal of the axle being less in diameter than the axle itself, but the shoulder C, on one side, and the flange D at the other side, are the same diameter of the axle; the ends of the cylinders E operating between the shoulder C and flange D, which make the axle B revolve correctly and truly, and prevent the axle from slipping sidewise or wobbling.

On the journals G G, of the cylinders E, are anti-

friction rollers H, that revolve on sectional rings or ends J, in four divisions or sections, 1, 2, 3, 4, each section having two or more rollers, H, with their journals operating in slots or apertures in the sectional ends J.

These sectional rollers likewise assist in reducing the friction or heating of the axle B, and they are in sections, so as to be easily placed upon the journals G, of the cylinders E, or removed when required, without removing the axle or cylinders from the box, the outside circular plates K K securing the rollers to their places, and preventing the sections from working out.

The oval plate L, on the side of the box A, is intended to prevent the dust from getting into the box, by having a packing of yarn or gum-elastic ring around the axle, and securing the packing by fastening the oval plate L over it by screws.

What I claim as my invention, and desire to secure by Letters Patent, is—

The combination and arrangement of the cylinders E, with their sectional rollers H, operating on the upper side of the journal of the axle B, and secured by the shoulder C and flange D, as herein described, and for the purposes set forth.

W. E. WILCOX.
